US00D856040S

(12) United States Design Patent (10) Patent No.: US D856,040 S
Fluegge et al. (45) Date of Patent: * Aug. 13, 2019

(54) MERCHANDISER PARTS(71) Applicant: Retail Space Solutions LLC, Milwaukee, WI (US)(72) Inventors: Craig A. Fluegge, Menomonee Falls, WI (US); Christopher J. Turner,
Pewaukee, WI (US)(73) Assignee: Retail Space Solutions LLC, Milwaukee, WI (US)() Term: 15 Years(21) Appl. No.: 29/577,333(22) Filed: Sep. 12, 2016(51) LOC (12) Cl. .... 06-06(52) U.S. Cl. D6/675
USPC ....(58) Field of Classification SearchUSPC ... D6/552, 572-574, 675, 675.2, 705, 705.1, D6/705.2, 705.6, 705.7, 706CPC A47F 5/0018; A47F 5/01; A47F 5/0031; A47F 5/0081; A47F 5/0093; A47B 96/02

Primary Examiner — Kelley A Donnelly

(74) Attorney, Agent, or Firm — Andrus Intellectual Property Law, LLP(57) CLAIMWe claim the ornamental design for merchandiser parts, as shown and described.DESCRIPTIONFIG. 1 is a top perspective view of merchandiser parts according to our new design;FIG. 2 is a bottom perspective view of the merchandiser parts in FIG. 1;FIG. 3 is a right side elevation view of the merchandiser parts in FIGS. 1-2;FIG. 4 is a left side elevation view of the merchandiser parts in FIGS. 1-3;FIG. 5 is a front elevation view of the merchandiser parts in FIGS. 1-4;FIG. 6 is a rear elevation view of the merchandiser parts in FIGS. 1-5;FIG. 7 is a top view of the merchandiser parts in FIGS. 1-6; and,FIG. 8 is a bottom view of the merchandiser parts in FIGS.
1-7.The merchandiser parts shown in broken lines in the figures depict unclaimed environmental subject matter, are for illustrative purposes only, and form no part of the claimed design.1 Claim, 7 Drawing Sheets# US D856,040 S
